Primary Examiner—Doris Clark[57] **CLAIM**

The ornamental design for an adjustable ladder stabilizer, as shown and described.

DESCRIPTION

FIG. 1 is a front elevational view of the adjustable ladder stabilizer showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

In FIG. 1, the dotted line showing of a ladder is for environmental purposes only and forms no part of the claimed design.
